INTERNAL COMBUSTION ENGINE

Filed Oct. 20, 1930

FIG. 1.

FIG. 2.

UNITED STATES PATENT OFFICE

FINN T. IRGENS, OF MILWAUKEE, WISCONSIN, ASSIGNOR TO OUTBOARD MOTORS CORPORATION, OF MILWAUKEE, WISCONSIN, A CORPORATION OF MICHIGAN

INTERNAL COMBUSTION ENGINE

Application filed October 20, 1930. Serial No. 489,793.

REISSUED

This invention relates to improvements in internal combustion engines.

It is the object of the present invention to increase the volumetric efficiency of an internal combustion engine. My invention is illustrated in a two cycle engine but certain features of it are applicable to any engine.

I seek to accomplish the indicated result in several different ways involving, first, the provision of a duplex valve structure and two separate mixture admission ports, thereby obtaining twice as much valve opening without increasing the dimensions of the parts as would be possible with the use of a single port of similar angular extent; secondly, by separately controlling the passages leading to the two ports opening into the crank case compression chamber and by advancing the timing of the valve controlling 20 the port which is open only at high engine speeds, whereby in effect to increase the valve opening at high engine speeds and thereby to compensate for the effect of mixture inertia at such speeds; thirdly, by varying the 25 relative dimensions of the passages leading to the respective ports so that the passage which is open only at high engine speeds will have somewhat greater capacity than the low speed passage, whereby additionally to 30 compensate for the effect of mixture inertia which is relatively pronounced at high engine speeds; and, fourthly, by using a multiple manifold and opening and closing the several manifolds successively, thereby approaching 35 a condition of constant velocity of mixture travel and avoiding the pockets and dead spots and condensation of fuel occasioned by the throttled passage of mixture at low velocity through a single manifold large 40 enough to handle efficiently the high velocity requirements.

It is my further purpose, by the passage design aforesaid, to tend to equalize the flow to the crank case compression chamber as 45 between the denser and lighter components of the mixture so as to ensure the proper delivery of all material, and particularly to increase the velocity in the lower of the passages to overcome the tendency of the heavier 50 material to collect therein. By cutting off the

upper passage altogether at high engine speeds, I force all of the mixture to traverse the lower passage, thereby maintaining as high a velocity in the lower passage at half speed as is existent at full speed. By thus 55 compensating my improved engine for changes of speed, I seek to obtain more power at higher speeds and more uniform results at all speeds than is possible in the use of any engine from which my invention is absent. 60

In the drawings:

Figure 1 is a fragmentary side of elevation of an outboard motor engine showing in vertical axial section the crank case of a two cylinder opposed two cycle engine embodying this invention, the fuel tank and other parts lacking in pertinency to the present disclosure being omitted.

Figure 2 is a detail view in transverse section, taken in the plane indicated at 2-2 in Fig. 1.

Figure 3 is a detail view in horizontal section, taken in the plane indicated at 3-3 in Fig. 1.

Figure 4 is a detail view of the intermediate 75 crank disk as it appears when viewed in plan, one of the crank pins being shown in cross section taken in the plane indicated at 4-4 in Fig. 1.

Figure 5 is a view taken in horizontal section in the plane indicated at 5-5 in Fig. 1.

Like parts are identified by the same reference characters throughout the several views.

The bracket 6 carries a bearing sleeve 7 in which the engine support 8 is swiveled. 85 Mounted on the engine support is the closure cap 9 for crank case 10, the crank case and closure cap having aligned bearings 11 and 12 for the crank shaft 15.

Opening oppositely into the interior compression chamber of crank case 10 through the ends thereof, are the ports 16 and 17 leading to which are manifold passages 18 and 19 respectively, which are formed in the metal of the crank case. A carburetor 20 provides extensions of these passages uniting in the jet passage 21 into which jet 22 projects laterally from float chamber 23. The carburetor 95 provides a tapering partition at 24 which divides the extension of passages 18 and 19 100

and co-acts with the throttle valve 25 which comprises a segment of a cylinder journaled in a cylindrical extension of jet passage 21 as shown in Figs. 1 and 2.

5 The inlet fitting 27 provides an extension of the jet passage 21 whereby such passage is bent back upon itself across the throttle valve chamber, thereby protecting the inlet from spray in outboard motor use. A choke valve at 28 restricts the inlet passage for the usual purpose.

10 The upper and lower inlet ports 16 and 17, whereby the mixture is admitted to the crank case, are controlled by crank cheek valves 29 and 30 which are preferably integral with the crank shaft 15 and connected by cranks 31 and 32 and an intermediate cheek 33. Each of the upper and lower cheeks 29 and 30 has a segmental opening registerable with its respective port 16 or 17, as shown in Figures 20 3 and 5. The respective openings in the valve cheeks 29 and 30 are preferably extended into the crank shaft at 34, as shown in Figure 5, thereby greatly increasing the volumetric efficiency of the valve by increasing its area without changing its overall dimensions.

25 It is particularly to be noted that the segmental opening in valve disk 29 is angularly advanced with respect to the segmental opening in valve disk 30, and as a result, port 16 will be opened and closed somewhat earlier than port 17. Figures 3, 4 and 5 show the relative positions of the parts in a given 35 crank shaft position, and it will be observed that the valve disk 29 has a partially uncovered port 16 in Figure 3, while disk 30 is just at the point of uncovering its port 17 in Figure 5. The disposition of throttle valve 25 with respect to manifold passages 18 and 19 40 is such that passage 19 is first to open and last to close. Thus, passage 18 and port 16 are used only at relatively wide open positions of the throttle valve and consequently 45 high engine speeds.

50 Theoretically, the valve timing, like the ignition timing, should be advanced at high engine speeds, since the inertia of the mixture is such that an appreciable amount of time is required to set it in motion and stop it. At high engine speeds the time interval 55 available for starting and stopping the mixture has decreased and in order to compensate for this decrease the valve timing should be advanced, particularly as to the time of opening. This is impractical in an ordinary single manifold engine, but since dual manifolding is being used in this engine and since 60 dual valves are provided to open and close the respective manifold ports, it becomes possible to approach optimum conditions by advancing the timing of one valve with respect to the other and thereby increasing the relative period for which mixture is admitted 65 to the crank case chamber and advancing the

relative time at which mixture is first set in motion by the opening of the valve.

Figure 1 shows the position of the throttle valve at full engine speed. It will be observed that manifold passage 18 is larger 70 than manifold passage 19, thereby compensating for increased resistance to flow at high mixture velocities. As the throttle valve is closed, passage 18 will be wholly cut off, while passage 19 remains open. And because of 75 the reduction in engine speed and consequently reduced demand for mixture, the velocity through passage 19 under these circumstances will be approximately the same as the velocity through this passage at wide open throttle. The smaller passage is preferably beneath the larger so that the continuous flow of mixture through the smaller passage whenever the engine is running will keep this passage free of accumulations of unvaporized 80 fuel.

85 Another reason for putting at the bottom of the crank case the inlet passage which is open at all times when the engine is running, lies in the fact that the disk valve 30 has a 90 better seal at the bottom of the crank case than is possible between valve 29 and the top of the crank case. The engine shown is arranged upon a vertical axis so that the weight of the crank shaft, fly wheel and associated 95 parts is carried by the crank case through the crank cheek and valve disk 30. The close fit between disk 30 and the bottom of the crank case minimizes leakage at this point and any leakage which occurs past disk 29 will be unimportant for the reason that at low speeds the passage 18 is wholly cut off by throttle valve 25 and at high speeds the slight amount of leakage which might occur would be unimportant.

100 The use of multiple manifold passages and admission ports makes it possible to double the area of valve opening without increasing the size of the parts, thereby greatly increasing volumetric efficiency. It will be obvious that by using additional valves and manifolds, a still further increase could be made, each manifold being preferably cut off in succession in order to approach a condition of substantially constant velocity 110 through the several manifolds.

115 The peculiar form of the central cheek 33 is determined by its weight and the desirability of disposing that weight in a manner to counterbalance the loss of weight in cheeks 120 29 and 30 occasioned by the provision of the segmental openings therein.

125 Although I have chosen to illustrate the application of this invention to a two cylinder two cycle engine of conventional design having a single crank case chamber, those skilled in the art will readily understand that the provision of multiple manifolding and multiple valve control subject to throttle means for opening and closing the manifolds successive- 130

ly, is a feature applicable to any kind of internal combustion engine.

This application is a continuation in part of my application, Serial No. 405,561, filed 5 November 8th, 1929, and contains claimed subject matter divided therefrom.

I claim:

1. In an internal combustion engine, the combination with a mixture receiving chamber and a plurality of mixture delivering passages leading to said chamber, of means for supplying mixture to the several passages and throttle valve means operatively controlling the several passages and adapted to open 10 and close them successively.

2. In an internal combustion engine, the combination with a mixture receiving chamber and a plurality of mixture delivering passages leading thereto, of mechanically operated valve means controlling the time of mixture delivery to said chamber, means for supplying mixture to the several passages, and throttle valve means for successively opening 20 and closing said passages.

3. In an internal combustion engine, the combination with a mixture receiving chamber and a plurality of mixture delivering passages leading thereto, of mechanically operated valve means controlling the time of mixture delivery to said chamber, means for supplying mixture to the several passages, and throttle valve means for successively opening 30 and closing said passages, the mechanically operated valve in the passage last opened by said throttle valve means being timed to open in advance of the opening of the mechanically operated valve in another of said passages.

4. In an internal combustion engine provided with a crank shaft and a mixture receiving chamber, the combination with a plurality of manifold passages leading to said chamber, and means for supplying mixture to each of said passages, of rotary valve members connected with said crank shaft for the individual control of delivery of mixture to said chamber from each of said passages in timed relation to the operation of said shaft, and manually operable throttle valve means 50 for successively opening and closing the several passages.

5. In an engine, the combination with a mixing chamber and a mixture receiving chamber of a plurality of manifold passages 55 affording potential communication between said chambers and throttle valve means for successively opening and closing said passages.

6. In an internal combustion engine, the combination with a mixing chamber and a mixture receiving chamber, of a plurality of manifold passages affording communication between said chambers and varying in cross-sectional area, and throttle valve means 65 for successively opening and closing the sev-

eral passages, a passage of relatively large area being last to open and first to close.

7. The combination in an internal combustion engine with a mixing chamber and a mixture receiving chamber, of a plurality of manifold passages affording communication between said chambers at differing levels, and a throttle valve for successively opening and closing said passages, the lowest of said passages being the first to be opened and the 75 last to be closed.

8. In an internal combustion engine, the combination with a crank shaft, a mixing chamber and a mixture receiving chamber, of a plurality of manifold passages affording communication between said chambers and provided with individual valves controlling the delivery of mixture to said receiving chamber, and means connecting the respective valves with the crank shaft for opening and closing in consecutively timed relation. 80

9. In an internal combustion engine, the combination with a crank shaft, a mixing chamber and a mixture receiving chamber, of a plurality of manifold passages affording communication between said chambers and provided with individual valves controlling the delivery of mixture to said receiving chamber, and means connecting the respective valves with the crank shaft for opening 90 and closing in consecutively timed relation, and throttle valve means for successively opening and closing communication between said mixing chamber and passages, the passage timed for first opening by the crank shaft operated valve being last opened and first closed by said throttle valve means. 95

10. In an engine, the combination with an upright shaft carrying valve disks, and a mixture receiving chamber provided with ports controlled by said disks, of a carburetor or mixing chamber, upper and lower manifold passages extending from said mixing chamber to said ports, and a throttle valve movable successively across the openings of 100 said passages. 110

11. In a two cycle engine, the combination with a crank case compression chamber provided with ports and a crank shaft, of crank shaft operated valve means controlling the respective ports and timed for the opening and closing of one port in advance of the respective opening and closing of the other, a carburetor provided with a mixing chamber, manifold passages leading from the mixing chamber to the respective ports, and an oscillatable throttle valve movable successively across the openings of said passages from 115 said mixing chamber. 120

12. In an internal combustion engine provided with valve controlled ports and a mixing chamber adapted to deliver mixture through said ports, of means connected with the throttle valve for varying the proportion 130

of the engine cycle during which mixture passes from said chamber to said ports.

13. In an internal combustion engine adapted for a predetermined cycle of operations, the combination with a mixture receiving chamber and a mixing chamber, of valve means engine operated for controlling communication between said mixture chamber and receiving chamber and arranged to open during a predetermined portion of the engine cycle, and means operable in accordance with changes of engine speed for advancing and retarding the time in the cycle at which communication is established between said chambers.

14. In an internal combustion engine, the combination with a crank case having upper and lower ports and an upright crank shaft mounted for rotation in said case and provided with valve members having openings registerable with the respective ports, of a carburetor mixing chamber, manifold passages leading from said chamber to the respective ports, and an oscillatable throttle valve movable successively across said passages.

15. An internal combustion engine of the type having crank case compression, said engine comprising a crank case, a crank shaft rotatable therein, manifold passages leading to said crank case, valve means connected with said crank shaft for controlling communication between said passages and case, means for supplying carbureted air to said passages, and throttle valve means adapted to open and close said passages successively.

16. A two cycle internal combustion engine comprising the combination with a vertical crank shaft and a crank case provided with upper and lower bearings for said shaft, of crank cheeks carried by said shaft and operating adjacent the top and bottom of said crank case, said cheeks being provided with openings and the ends of said crank case being provided with ports, carbureting means for supplying mixture to said crank case, a plurality of manifold passages adapted to deliver the mixture from the carbureting means to said ports subject to the control of said crank cheeks, and throttle valve means for the respective passages positioned for the successive opening and closing thereof.

17. A two cycle internal combustion engine comprising the combination with a vertical crank shaft and a crank case provided with upper and lower bearings for said shaft, of crank cheeks carried by said shaft and operating adjacent the top and bottom of said crank case, said cheeks being provided with openings, and the ends of said crank case being provided with ports, carbureting means for supplying mixture to said crank case, a plurality of manifold passages adapted to deliver the mixture from the carbureting means to said ports subject to the control of said crank cheeks, and throttle valve means for

the respective passages positioned for the successive opening and closing thereof, one of said passages being of larger cross section than the other and extending thereabove and arranged to be last opened by said throttle valve means.

18. A two cycle internal combustion engine comprising the combination with a vertical crank shaft and a crank case provided with upper and lower bearings for said shaft, of crank cheeks carried by said shaft and operating adjacent the top and bottom of said crank case, said cheeks being provided with openings, and the ends of said crank case being provided with ports, carbureting means for supplying mixture to said crank case, a plurality of manifold passages adapted to deliver the mixture from the carbureting means to said ports subject to the control of said crank cheeks, and throttle valve means for the respective passages positioned for the successive opening and closing thereof, one of said passages being of larger cross section than the other and extending thereabove and arranged to be last opened by said throttle valve means.

19. In a two cycle engine, the combination with a compression chamber provided with air admission ports, of a crank shaft, crank shaft operated valve means controlling the respective ports and timed for the opening and closing of one port in advance of the respective opening and closing of the other, and throttle valve means for successively throttling air admission to said ports.

20. In a two cycle engine, the combination with a compression chamber provided with ports, of a crank shaft, crank shaft operated valve means controlling the respective ports and timed for the opening and closing of one port in advance of the respective opening and closing of the other, an air inlet chamber arranged for air delivery to the respective ports, and means for successively throttling communication between said air inlet chamber and ports, said means being adapted to throttle communication with the port first opened by said crank shaft operated valve means before throttling communication with the port later opened by said valve means.

21. In a two cycle engine, the combination with a compression chamber provided with air admission ports and manifolds leading thereto, of a crank shaft, crank shaft operated valve means controlling the respective ports and time for the closing of one port in advance of the closing of the other, and throttle valve means associated with the respective manifolds and organized for the successive throttling of air admission therethrough to said ports.

22. In a two cycle engine, the combination with a crank case compression chamber provided with air admission ports, of a crank

shaft operating in said chamber, crank shaft operated valve means controlling the respective ports and timed for the closing of one port in advance of the closing of the other, a carburetor mixing chamber communicating with the respective ports and throttle valve means for successively throttling communication between said mixing chamber and the respective ports.
